UNITED STATES PATENT OFFICE.

REUBEN A. MCHENRY, OF WINFIELD, KANSAS, ASSIGNOR OF ONE-HALF TO
ALBERT L. BLANKENMEISTER, OF SAME PLACE.

STONE OR MARBLE DRILL.

SPECIFICATION forming part of Letters Patent No. 394,787, dated December 18, 1888.

Application filed May 14, 1888. Serial No. 273,826. (No model.)

To all whom it may concern:

Be it known that I, REUBEN A. MCHENRY, of Winfield, in the county of Cowley and State of Kansas, have invented a certain new and useful Improvement in Stone and Marble Drills, of which the following is a full, clear, and exact description, reference being had to the accompanying drawings, forming part of this specification.

10 This invention relates to devices for the adjustment and clamping of marble and stone blocks and monuments while under the process of drilling and means for drilling the same; and the invention consists in features 15 of novelty hereinafter fully described, and pointed out in the claims.

Fig. I is an elevation of my drilling apparatus, and shows the adjustable frame, center-bearing rest, clamp-frame, and drill 20 drilling socket-holes in the die-section of a monument for seating the dowel-pins that secure it to its base. Fig. II is a horizontal section taken on line II II, Fig. I, and shows the action of the clamp-frame in securing the 25 block or monument while under treatment. Fig. III is a horizontal section taken on line III III, Fig. I, and shows the longitudinally-adjustable bar that carries the drill; and Fig. IV is a detail of one of the side posts, and shows 30 the hook for fastening the clamp when said clamp is raised in its inoperative position.

Referring to the drawings, in which similar figures of reference indicate like parts in all the views, 1 represents the side posts; 2, the 35 bottom bar; and 3, the upper bar, which is provided with an elongated slot, 39, as shown; or, if desired, the required aperture provided by the elongated slot may be obtained by two parallel narrow bars instead of the one wide 40 one. A longitudinally-adjustable cross-bar, 4, is provided with elongated tenons 5 at its ends, which are worked endwise in the mortises 6 in the posts when it is desired to move the drill, which it carries laterally over the face 45 of the block or monument.

7 represents a box-screw, the foot-flange around which is perforated, and through said perforations 9 screw-bolts 10 are passed and into the said cross-bar, to which they firmly 50 secure it. A vertical screw-shaft, 11, passes

through a perforation, 12, in the cross-bar 4 and engages within said box-screw, in which it is adjusted vertically by the hand-wheel 13, which is tight-keyed to it near its lower end. A cup, 14, with a globular or semi-globular 55 socket, 15, is secured to the lower end of said screw-shaft, and the surmounting pressure-ball terminal 16 of the crank-brace 17 fits in said socket, making together a ball-and-socket boxing. The ball may either be allowed to turn with said socket or the upper vertical arm of the brace may turn in a loose bearing within the ball. The drill-bit 18, which is changeable from one size to another, may be firmly secured by any suitable means 60 in its seat in the brace. A series of bracket-cleats, 19, are screw-bolted or otherwise secured to the insides of the posts of the frame, and an adjustable platform-bar, 20, is seated on the corresponding cleats on said posts 65 that best accord with the length of the block or monument-spire to be drilled.

21 represents a monument-spire, the die 24 of which is in the course of being drilled to provide the socket-holes that seat the dowel- 70 pins which secure the monument to its base.

22 is the inverted pinnacle of the monument-spire, that rests in the conical socket 23 in the middle of the platform 20. The monument is steadied in its inverted vertical position by means which are now to be described.

25 represents the clamp-frame, which is secured by the hinge 26 to the projecting lug 27, that is screw-bolted to one of the side posts of the frame. The clamp has bifurcated arms 85 28, provided with terminal perforated screw-threaded lugs 29, in which the clamping set-screws 30 work when actuated by the disk-wheels 31.

Swivel-boxes 32 are secured to and have 90 loose bearings on the ends of the clamping set-screws 30, and secured within said boxes and projecting therefrom are rubber cushions 33, which intervene between the swivel-boxes and the monument 24, and so present a soft 95 clinging frictional surface which is immovable on the die-section of said monument, as the clamp-screw swivels or turns freely in the boxes, which, after the frictional clutch of the cushion on the marble, do not rotate. Con- 100

sequently, while they insure a sufficient clutch-hold, their grasp is of no injury to the most highly polished marble.

When the clamp-frame is out of use, it may be turned up erect on its hinge, as shown in dotted lines in Fig. I, and the hook 34, which hangs on the staple 35, (that is driven into the post of the frame on that side,) is then made to engage with the bracket-loop 36, and retains the clamp-frame in its erect position. When the clamp-frame is thus erected, it clears the track for the placement of the platform 20 and the monument 24 or any marble or stone block about to be drilled that is to be seated on the platform 20. The clamp-frame is then unhooked and let down into its operative position, as shown in full lines in Figs. I and II, and the clamp set-screws on the corresponding sides of the clamp-frame are then screwed up to hold the monument or other object securely while it is being operated on.

The drill is especially intended for use in marble-works for drilling dowel-holes 38 in the die-sections, &c., of monuments, also in head-stone bases, &c., for dowel-pinning the sections together; but it may also be advantageously used for other drilling purposes and for holding monuments, tombstones, &c., while in the course of lettering, decorating, &c.

It will be seen that the platform 20 is removable from the bracket-cleats at one height on the frame to any other to adapt the adjustment to the height of the block or monument to be operated on.

I claim as my invention—

1. In a stone and marble drill, the frame in which the drill is hung, the hinged bifurcated clamp-frame, and adjustable clamping set-screws arranged to hold the monument, &c., in course of drilling, substantially as and for the purpose set forth.

2. In a stone and marble drill, the main frame, the longitudinally-adjustable bearer-bar 4, the screw-boxing secured to said bar, the screw-shaft that engages in said boxing and passes up through the elongated slot in the cross-bar of the main frame above, the drill brace and bit, and the ball-and-socket connection of said brace with said screw-shaft, and hand-wheel that operates the shaft to adjust the elevation and depression of the drill, substantially as and for the purpose set forth.

3. In a stone and marble drill, the main frame, the bracket-cleats on said frame, and adjustable supporting-platform that rests on said cleats, the said platform provided with an inverted conical socket in which the pinnacle of the monument, &c., rests while in the process of drilling, and the hinged clamp-frame and set-screws that hold the monument, &c., while being drilled, substantially as and for the purpose set forth.

4. In a stone and marble drill, the main frame, the adjustable cross-bar from which the drill is suspended, the supporting-platform, the hinged bifurcated clamp-frame, the hooked attachment to connect the main frame to the clamp-frame when the latter is inoperative, the clamping set-screws that work in the terminals of the bifurcated ends of the clamp-frame, and the swivel-boxes and their inclosed rubber cushions on the inner ends of the set-screws arranged to provide a friction-surface bearing not injurious to the face of the marble, substantially as and for the purpose set forth.

REUBEN A. McHENRY.

In presence of—

A. L. SCHULTZ,
G. H. BUCKMAN.
